COMBINED CAN-OPENER MAGNET AND HOUSING THEREFOR

Ira P. Rhodes, St. Louis, Mo., assignor to Swing-A-Way
Manufacturing Company, St. Louis, Mo., a corporation
of Missouri

Application April 6, 1956, Serial No. 40,958

Term of patent 14 years

(Cl. D26—1)

Fig. 1 is a top plan view of a combined can-opener magnet and housing therefor, showing my new design;

Fig. 2 is a side elevational view, showing the hollow upper portion and the annular mounting post;

Fig. 3 is a bottom plan view thereof, a housed magnet being illustrated in place;

Fig. 4 is an opposite side elevational view; and

Fig. 5 is an end elevation view thereof, the opposite end being identical thereto.

I claim:

The ornamental design for a combined can-opener magnet and housing therefore, as shown and described.
